4 Claims. (Cl. 214—6)

This invention relates to machines for stacking and/or unstacking articles such as boxes, milk cases, or the like. The invention as disclosed herein is adapted to receive successive articles to be stacked from a line of such articles moving along on a conveyor, stack the articles, and discharge the stack from the machine. In the alternative, a machine embodying the invention as disclosed herein is adapted to receive successive stacks of articles from a line of such stacks moving on a conveyor and unstack each stack, discharging the unstacked articles from the machine.

A primary object of the invention is the provision of a stacking and/or unstacking machine which is fully automatic in operation, is of small, compact size in relation to the operation it performs and the articles it handles, which may be fabricated at a low cost, and installed with a minimum of disturbance of the article conveyors with which it is to be associated.

Another object of the invention is the provision of a machine which will stack boxes or cases moving one behind the other on a conveyor which runs through the machine by picking successive cases upwardly off the conveyor to place each case so removed beneath a case previously removed until a stack of determined height has been accumulated, and thereafter place the stack back on the conveyor from which the cases were originally drawn so that the stack may be discharged from the machine.

Another object of the invention is the provision of an unstacking machine adapted to receive successive stacks of boxes or cases from a conveyor running through the machine and which will successively remove the lowermost case of the stack and place it on the same conveyor by which the stack entered the machine so that the case may be discharged from the machine, and automatically repeat the operation until all of the cases of successive stacks have been discharged from the machine.

Another object of the invention is the provision of a case stacking machine which includes a reciprocating case elevator operable to raise successive cases off of a case conveyor and place them on cooperating case supporting means which supports each case spaced above the conveyor a distance exceeding the height of the following case, with the means for supporting the cases above the conveyor being automatically retracted to place the cases so supported on the following case as the same is raised by the elevator, and with such supporting means being extensible to support the last raised case and those resting thereupon to allow the elevator to return to a lowered position preparatory to raising the next following case.

Another object of the invention is the provision of a case unstacking machine which includes an elevator for raising a stack of cases off of a case conveyor with a case holding device operable synchronously with the elevator to support the stack of cases above the lowermost case and hold such stack elevated as the elevator moves downwardly to place the lowermost case on the conveyor, and which stack holding device will release the stack when the elevator returns upwardly from the conveyor after a previously unstacked case has been discharged from the machine to allow the elevator to lower the stack the height of the bottom case and thereafter again support

2

the stack as the elevator lowers the bottom case to the conveyor with the cycle repeating until all of the cases of the stack have been deposited by the elevator on the conveyor and discharged from the machine.

5 Another object of the invention is the provision of an article handling machine which is selectively operable to stack cases at one time and unstack cases at another time, with whichever operation desired being selected by the machine attendant. While hereinafter the invention is described and claimed in connection with case stacking and unstacking, it should be understood that the word case is used broadly to describe boxes, crates, and the like.

Other objects, advantages, and meritorious features 10 will more fully appear from the specification, claims, and accompanying drawings wherein:

FIG. 1 is a top view of a machine embodying the invention;

FIG. 2 is a cross sectional view taken on the line 2—2 15 of FIG. 1;

FIG. 3 is a cross sectional view taken on the line 3—3 of FIG. 2;

FIG. 4 is a cross sectional view taken on the line 4—4 20 of FIG. 3;

FIG. 5 is a schematic view showing the relative positions between cases during the stacking operation;

FIG. 6 is a schematic view showing the relative positions of cases during an unstacking operation;

FIGS. 7 and 8 are schematic views of the electrical 30 control system of the machine, FIG. 7 relating primarily to that portion of the system which is operative when case stacking is selected, and FIG. 8 relating to that portion of the system which is operative when unstacking is selected.

The machine described herein is particularly well suited for the stacking or unstacking of milk bottle cases and when used as a stacker in a dairy, is positioned over a case conveyor carrying filled cases away from the machine which deposits the milk bottles in the cases. In 40 the event the machine is to be used as an unstacker, it is positioned over the case conveyor somewhere ahead of the station at which the empty bottles are removed from the cases, or in the event of the cases being used for packing paper cartons of milk and where the cases are returned empty to the dairy, the machine would be positioned ahead of the case washing machine. Where the machine is to be used in a dual capacity, i.e., at one time as a stacker and at another time as an unstacker, the conveyor system with which it is associated will have a 45 single conveyor common to the machine which is capable of operation in opposite directions and during operation in one direction will deliver stacks of cases to the machine for unstacking, and when operated in the other direction will deliver single cases to the machine for stacking.

The machine disclosed herein stacks and unstacks cases from the bottom. In other words, rather than placing successive cases one on top of the other as would normally be done by hand in building a stack, this machine places successive cases one beneath the other 55 to build the stack. In unstacking, the machine withdraws successive cases from the bottom of a stack rather than withdrawing the cases from the top of the stack. The unstacking operation is essentially merely the reverse of the stacking operation with certain variations.

The machine as disclosed herein has been designed for use with what is termed an "in-floor" conveyor, which type of conveyor is coming into widespread use in the dairy industry. The machine is simply placed in the floor through which the in-floor conveyor travels with provision being made to allow the case lifting fingers of the case elevator to drop below the case supporting surface 60 of the conveyor.

A typical installation for handling conventional milk bottle cases of a size approximately 14" long by 11½" wide, would occupy a space roughly 3'4" square centered over the case conveyor and with the height of the machine being substantially equal the height of the stack of cases to be handled. The machine, generally indicated at 20, is adapted to rest on the floor over which the cases are conveyed by the case conveyor 22. The case conveyor serves to deliver cases to and discharge cases from the machine, and is a conventional double chain conveyor. The cases rest on the chains and as the chains move, the cases are frictionally carried therewith. The machine has a frame comprising, as best shown in FIGS. 1 and 2, four upright channel members 24, 26, 28, and 30, which are secured by angle plates 32, 34, 36, and 38 to a pair of floor plates 40 and 42 disposed on opposite sides of the case conveyor 22. The floor plates may in turn be secured to the floor of the building as by bolts or the like 44. Disposed at opposite sides of the conveyor 22 and carried by this frame is the vertically shiftable case elevating and lowering mechanism indicated generally at 46, as well as the case retaining mechanism which includes the supporting mechanism 48 and the case holding or clamping mechanism 50, the latter being operative only during unstacking.

Tie plates 52 are secured to uprights 24 and 26 as shown in FIGS. 1 and 2, and a similar tie plate, not shown, rigidifies uprights 28 and 30. Another tie plate 54 extends across conveyor 22 spaced thereabove so as not to interfere with case travel on the conveyor and is secured between and to the upper ends of uprights 26 and 30 to tie the upper ends of the framework on opposite sides of the conveyor together.

Assuming the machine is to be used for stacking cases, the cases C enter the machine on the case conveyor 22 in the direction of arrow S in FIG. 1, one behind the other. As the leading case passes between uprights 26 and 30 and its leading edge is about one-half the way through the machine, it strikes the arm 56 of switch LS-1, which in turn activates fluid pressure cylinder 58 to withhold the advance of those cases following the leading case. Cylinder 58 is pivotally connected at 60 to a bracket 62 secured to upright 30 and at the opposite end has a piston rod pivotally connected at 64 to a case stop 66, in turn pivotally supported by a bracket 68 secured to upright 30. As LS-1 is tripped, it causes pressurization of cylinder 58 to pivot the stop 66 from the solid to the phantom outline position in which the stop presses against the case next following the leading case and withholds its movement.

The leading case continues to travel until it comes into abutment with the extended case locators 74 and 76. The case locators are a pair of abutments or stops, one at each side of the path of case travel, which are extensibly and retractably carried by bearings 78 and 80 secured to uprights 28 and 32, and are actuated for such movement by fluid pressure cylinders 82 and 84, also mounted in any convenient fashion on uprights 28 and 32. As will hereafter appear, these locators remain in the extended position during the stacking operation and retract to let a stack pass out of the machine on conveyor 22 at the end of the stacking operation.

When the case actuates switch LS-1, such switch initiates a time delay relay TR-1, which relay measures a determined interval of time sufficient to allow the case to reach the locators 74 and 76 and then causes the case elevator 46 to start its rising operation to lift the case off the conveyor to a height above that of the following cases. The case elevator includes four case lifting fingers indicated at 118, 118_a, 120, and 120_a, and hereinafter more fully described. As the case rises, case supports 86, 86_a, 88, and 88_a above it retract, allowing any cases supported thereon to be placed on the ascending case and to allow the ascending case to pass by the supports. When the ascending case reaches a position above the supports, they

are again extended, the elevator reverses its travel, and during descent places the case on the supports and continues back down to its starting position to repeat the operation.

The elevator comprises a pair of identical mechanisms on opposite sides of the conveyor 22 and disposed between the uprights of the frame. Each such mechanism includes a pair of vertical rods 96 and 98 for one mechanism, and 100 and 102 for the other. Hereafter a description of one such mechanism will suffice for both. The rods are mounted on the upright frame members in blocks 99 and 101 secured to the frame members and to opposite ends of the rods. Supported for vertically slidable movement on the rods is an elevator carriage which includes a pair of vertical members 104 and 106 having rod bearings 108, 110, 112, and 114 secured thereto and received upon the rods, with a horizontal cross member 116 extending between and secured to the upper ends of members 104 and 106. Secured to the lower end of the carriage and specifically to the lower ends of members 104 and 106 are the elevator fingers 118 and 120 which, as will be noted with respect to finger 118 in FIG. 3, extend beneath the path of travel of a case on conveyor 22.

The elevator fingers are raised and lowered by a fluid pressure cylinder 122 which acts upon the elevator carriage. Cylinder 122 is secured at the lower end to the floor plate 42, and at the upper end has a piston rod 124 connected to the cross piece 116 of the carriage. Upon pressurization of the cylinder at the lower end the fingers are raised, while pressurization at the opposite end causes the fingers to be lowered. The complementary elevator fingers 118_a and 120_a on the opposite side of the case conveyor cooperate with fingers 118 and 120 to raise cases off the conveyor or replace elevated cases on the conveyor. The fingers come up simultaneously beneath the bottom of the cases to raise them from the conveyor.

The case supports 48, which hold the previously raised cases elevated as succeeding cases are brought up to be stacked beneath those held by the supports, comprise the aforementioned four fingers 86, 86_a, 88, and 88_a, which are mounted for extensible and retractable movement with two of the fingers disposed on each side of the conveyor 22 and at a height thereabove so that they will clear the top of the highest case which may be stacked or unstacked by the machine. A description of one pair of fingers as shown in FIGS. 3 and 4 will suffice for both pairs. The fingers are carried by sleeve bearings 126 and 128 slidably mounted on rods 130 and 132, which are carried at opposite ends by vertical plates 134 and 136 upstanding from and secured to the floor plate 42. A cross member 138 extends between and is secured to the fingers behind the sleeve bearings to prevent revolution of the fingers on the rods. The fingers are disposed just beyond the edges of vertical plate 134 and reciprocate from a retracted position shown on both sides of conveyor 22 at 86 and 86_a in FIG. 6 and an extended case supporting position shown at 86 and 86_a in FIG. 5. A fluid pressure cylinder 139 suitably supported at one end on an angle member 141, secured to vertical plate 136, and having a piston rod 140 connected to cross member 138, is operative to extend and retract the pair of fingers 86 and 88, while a similar cylinder is operative to accomplish the same with the other pair of fingers 88 and 88_a.

Considering FIGS. 3 and 5, the sequence of operations in stacking cases may be readily comprehended. Assuming a case C-2 is supported by the supporting fingers, of which two are shown in FIG. 5 at 86 and 86_a, and another case rests on the case conveyor 22 and is in abutment with the locators 74 and 76, which are in the extended position shown in phantom outline, as mentioned herebefore the case has actuated LS-1 and after a short time delay the elevator starts its upward movement raising the elevator fingers, of which two are shown at 120 and 120_a. The fingers pick case C-1 off the conveyor and raise it toward the position occupied by case C-2. Just before

the upper edge of case C-1 strikes the case supports 86 and 86_a, switch LS-3, mounted on the upright frame member 30, is actuated by an adjustable trip 142 mounted on the elevator member 104. Actuation of switch LS-3 causes the case supports 86 and 86_a to be retracted to the position shown in FIG. 6. Because case C-1 is moving rapidly upwardly and the supports are withdrawn from beneath case C-2 when only substantially one-half inch or less exists between the two cases, case C-2 will drop only slightly, perhaps one-quarter inch, before it seats upon case C-1. With case C-2 now stacked on case C-1, both cases are elevated through the remainder of the stroke of cylinder 122. At the top of the stroke of cylinder 122, and assuming a full stack has not been accumulated, switch LS-4 is contacted by an adjustable trip 144 mounted on the elevator carriage and this reversely pressurizes the cylinders 139 to extend the case supports 86, 86_a, 88 and 88_a. When the case supports are extended, switch LS-7, mounted on the bracket 141 and having a switch arm in contact with the cross member 138 when the supports are retracted, is actuated to cause the elevator to lower cases C-1 and C-2 to the supports, upon which they are placed as the elevator returns to its starting position shown at 120 and 120_a in FIG. 5.

As cases C-1 and C-2 are now carried by the supports, another case may enter the machine for stacking. As the elevator reaches the bottom of its movement, it trips switch LS-5 mounted on the floor plate 42, which in turn reversely pressurizes case stop cylinder 58 to retract the stop 66 away from the case it is holding, allowing such case to enter the machine and trip switch LS-1 to repeat the above-described cycle.

As the stack of cases increases in height through repetition of the cycles, the machine automatically stops the stacking after a determined number of cases have been stacked, and the stack is thereafter sent out of the machine on conveyor 22. Secured to the machine frame are a pair of case stacking guides 150 and 152, each generally L-shaped in cross section and which extend beyond the height to which the cases are to be stacked. Mounted at the upper end of one of the guides is switch LS-6, the actuating arm 154 of which is contacted by the top case of the stack as the elevator is raising the entire stack to place it on the case supports. Upon actuation of LS-6, cylinder 122 is reversely pressurized and instead of continuing to raise the stack, the elevator returns it to conveyor 22 to be carried thereby out of the machine. LS-6 also serves to reversely pressurize cylinders 82 and 84 of the case locators, causing retraction of the locators out of the path of the stack so that the stack may leave the machine. As the stack leaves the machine and clears the locators 74 and 76, it trips switch LS-8, which causes pressurization of cylinders 82 and 84 to extend the locators and reversely pressurize cylinder 58 to allow the next case to enter the machine so the stacking cycles may continue.

FIGS. 7 and 8 are schematic views of the electrical control system of the machine with FIG. 7 relating primarily to the circuitry of such system operative when case stacking is selected. FIG. 8 shows the circuitry operative when unstacking is selected. A selector switch 160, when moved to the position shown in FIG. 7, will energize the circuit of FIG. 8 for unstacking operation of the machine, and when moved to the right to the phantom outline position shown, will de-energize the circuit of FIG. 8 and energize that portion of the circuit of FIG. 7 below the switch for stacking operation of the machine. As mentioned hereinabove the elevator, case locators, case stop, and case retaining mechanism are operated by fluid pressure. Such pressure is derived from a suitable pump driven by an electric motor schematically indicated at 162 in FIG. 7. Suitable fluid pressure lines extend from the pump driven by electric motor 162 to the various cylinders herebefore mentioned which actuate the case elevator, etc. Disposed in the pressure lines between the pump and the cylinders are solenoid operated spring re-

turn valves. The solenoids for the operation of such valves are shown in FIGS. 7 and 8 as at 164 for the solenoid that controls the valve which, in turn, controls the extension and retraction of the case locators 74 and 76. Each 5 solenoid operated valve, upon energization of its respective solenoid, serves to admit fluid pressure to the associated cylinder to cause extension of the piston rod of the cylinder, and upon de-energization of the solenoid the valve is spring-returned to a position redirecting fluid 10 pressure to the associated cylinder to cause retraction of the piston rod associated therewith. The circuits shown in FIGS. 7 and 8 include the limits switches LS-1, LS-4, etc., hereinabove mentioned. LS-1, shown in FIG. 7, is 15 provided with two throw arms, one being indicated at LS-1_a and the other at LS-1_b. LS-1_a is a normally open throw which is closed by a case entering the machine and contacting the arm 56. LS-1_b is a normally closed throw which is opened by a case entering the machine and striking the actuating arm 56. It will be noted that whether 20 the throws or switches are normally open or normally closed is indicated by whether the throw arm is above or below the circuit line in which the switch is schematically shown as connected.

Circuits 7 and 8 include a plurality of relays, the solenoids for which are enclosed in circles and give "CR" designations. The respective slave switches which are controlled by relay solenoids are also given "CR" designations followed by a number identifying the switch with the particular relay solenoid which controls it. As there 25 may be a number of enslaved switches controlled by a single relay solenoid, the various switches controlled by any particular relay solenoid are identified successively by alphabetical sub-scripts. The circuitry of FIG. 7 also includes a time delay type of relay indicated at TR-1, 30 which, upon energization for a determined time interval, will cause its enslaved switch TR-1_a to be closed. Upon deenergization of TR-1, switch TR-1_a will open. Certain 35 of the relay switches, such as CR-6_b, are normally closed, i.e., are closed when the controlling relay solenoid is deenergized, while relay switches such as CR-1_a are normally open and are closed only when the relay solenoids actuating such switches are energized. A further 40 description of the circuit of FIG. 7 is believed unnecessary as the operation of the machine can be traced through the circuit.

The structure of the machine thus far described is sufficient to stack cases entering the indexing station and release successive stacks from the station for discharge therefrom on the case conveyor 22. With certain 45 additions to the structure described, the machine may be made to unstack cases. Reference has heretofore been made to the unstacking circuit (FIG. 8) which would be operative during unstacking. With the exception of LS-3, the same limit switches are used during unstacking as 50 are used during stacking but the circuitry in which the switches are operated differs as will be evident from a consideration of FIGS. 7 and 8. Certain additional limit switches are provided when the machine is to be used for unstacking. It will be apparent that if the machine is to 55 be a dual purpose machine, i.e., one which will both stack and unstack, the additional switches necessary for the unstacking operation would be permanently a part of the machine and while they would be actuated during certain phases of the stacking operation, would have no 60 effect on the stacking operation.

In FIG. 1 a case stop similar to the case stop 58 heretofore described is secured to the right-hand end of the machine for the purpose of preventing or allowing entry of stacks of cases moving on conveyor 22 toward the 65 machine. Such case stop is of identical construction to that of the one heretofore described and therefore a further description is believed unnecessary.

One additional structural addition to the stacking machine to adapt it for unstacking is the case clamping mechanism 50 shown in FIGS. 3 and 4. Such mech-

anism includes a pair of clamping pads 166 and 168, one disposed at each side of a stack of cases in the machine and extensible and retractable to grip or release a case disposed between them. Such case gripping clamps are operable synchronously with the operation of the case supporting finger mechanism 48 during unstacking operation in a manner hereinafter described. Because the clamping pad 166 is carried by mechanism which is a duplicate of that supporting the pad 168, a description of the mechanism for pad 166 will suffice for both.

As shown in FIGS. 3 and 4, pad 166 is carried by a pair of push rods 170 and 172, which are received within rod supporting blocks or the like 174 and 176, which are mounted on a plate 178 which extends across the top of and is secured to the uprights 134 and 136. A hydraulic cylinder 180 is mounted on plate 178 with the piston rod 182 thereof connected to the push rods by a cross member 184. Upon pressurization of cylinder 180 in one direction, the push rods and consequently the pad 166 will be extended while upon reverse pressurization, the pad and push rods will be retracted. The pad moves between the solid outline position shown in FIGS. 3 and 5 and the phantom outline position bearing against a case as shown in FIG. 5 or the solid outline position shown in FIG. 6. Also included in the machine when adapted for unstacking are limit switches LS-9 and LS-10. Switch LS-9 is mounted on a cross member 188 which extends between and is secured to the bearing blocks 174 and 176. The switch has an actuating arm 190 which extends above the pad 166 to a point where it may be contacted and shifted by a case disposed between the clamps 166 and 168. Whenever a case is disposed between the clamps, switch LS-9 will be actuated. LS-9 is schematically shown in the circuit of FIG. 8. Switch LS-10 is disposed at the left-hand end of the machine to sense the discharge of successive cases from the machine during the unstacking operation and in this respect is similar in function to switch LS-8 heretofore mentioned in connection with the stacking operation. LS-10 includes two throw arms LS-10_a and LS-10_b, as shown in FIG. 8, both of which are closed by a case leaving the machine and contacting the switch actuating arm 192.

The unstacking cycle of the machine occurs as follows. Stacks of cases enter the machine successively on the case conveyor 22, the latter being operated in the direction of an arrow U shown in FIG. 1. The selector switch in the control system is shifted to the solid outline position shown in FIG. 7 de-energizing the circuit of FIG. 7 below the switch and energizing the circuit of FIG. 8. As the locators 46 are in the retracted position, the leading stack entering the machine will contact switch arm 56 to actuate LS-1 which, in turn, will energize the case stop solenoid to extend the stop 66_a to prevent the next following stack from interfering with the leading stack in the machine. As the leading stack moves farther into the machine, one of the cases will strike the actuating arm 190 of LS-9 serving to energize relay CR-10 in turn closing relay switch CR-10_a to energize time delay relay TR-1. Upon expiration of a determined time interval, TR-1 will close enslaved switch TR-1_a to energize the case elevation solenoid and cause the case elevator fingers 120 and 128 to lift the stack out of the indexing station. When the elevator reaches the top of its stroke, it closes switch LS-4 which, in turn, causes the elevator to descend. During descent of the elevator and when case C-2 has reached substantially the position shown in FIG. 5 during descent of the stack, switch LS-11 is closed energizing the clamp solenoid causing fluid pressure to be directed to cylinders 180 of both clamping mechanisms to cause extension of the clamps and gripping of case C-2. With case C-2 clamped and with the elevator continuing to descend, case C-1 will continue to descend and will be placed on conveyor 22 for discharge from the machine.

When the elevator bottoms, it closes switch LS-5, which serves to energize the case support solenoid controlling

extension or retraction of the supporting fingers 86 and 86_a. These fingers now extend beneath case C-2 to support it and when they are fully extended, serve to close LS-7, which in turn causes the de-energization of the case clamp solenoid causing retraction of the pads 166 and 168. As the first case to be unstacked leaves the machine and strikes arm 192 of LS-10, it closes LS-10_a and LS-10_b in turn causing the elevator to re-ascend. The elevator lifts case C-2 upwardly off the supporting fingers 86 and 86_a and when the elevator reaches the top of its stroke, LS-4_a and LS-4_b are closed reversing the movement of the elevator and the cycle repeats.

When the last case of the stack is lowered to the conveyor 22 for discharge from the machine, as no case will then be in contact with switch arm 190, circuit 8 is set up for the reception of the next stack of cases though the case stop 66_a does not retract until the last case of the previously unstacked stack of cases clears out of the machine and strikes arm 192 of switch LS-10. At this point the afore-described cycle will repeat.

From the above description it is now apparent that the machine disclosed herein can be used for either stacking or unstacking of cases simply by the selective positioning of switch 160 in the control system and by selecting the direction of movement of the case conveyor 22. It will be noted that when a stack of cases enters the machine, those cases above the lowermost case will come into contact with the stacking guides 150 and 152 which, in this event, serve as case stack locators and interrupt the travel of the stack of cases through the machine. The time delay cycle of time delay relay TR-2 may be so adjusted that substantially at the same instant that a stack of cases entering the machine comes into abutment with guides 150 and 152, the elevator will be caused to ascend to lift the stack off of the conveyor. It will also be noted that because of the particular way in which the machine is cycled during unstacking, the machine will cause unstacking of stacks of cases of varying heights anywhere from two or more cases in height. In the event that a single case should enter the machine when the machine is operating to unstack cases, such single case will pass directly through the machine without hindrance.

What we claim is:

1. A case unstacking machine comprising, in combination: an indexing station, a case conveyor running through the station, case stop means at the upstream side of said station relative to the movement of the case conveyor, case locating means in the station for interrupting movement of a stack of cases entering the station on the conveyor, a vertically reciprocable case elevator operable between a stack receiving position in the station and a stack elevated position above the conveyor, stack retaining mechanism disposed above the conveyor for receiving and holding a stack of cases raised therefrom by the elevator, said retaining mechanism operable to hold that case superjacent the case supported by the elevator during lowering of the supported case to the conveyor and responsive to the return of the elevator to a position supporting such superjacent case to release such superjacent case for lowering to the conveyor and hold the next superjacent case as the stack is lowered on the elevator toward the conveyor, and said case-retaining mechanism comprising case-supporting fingers extensible and retractable adjacent a stack of cases to extend beneath the lowermost case of the stack to support the stack, and further comprising case-gripping pads on opposite sides of a stack of cases and operable synchronously with the supporting fingers to grip a case prior to the extension of the supporting fingers therebeneath and release the case upon extension of the fingers therebeneath.
2. A case unstacking machine comprising, in combination: a case indexing station, a case conveyor running through the station, case stack retaining mechanism disposed above the station and including case supporting means and case clamping means, said case supporting

means including extensible and retractable case supporting elements at opposite sides of a stack of cases spaced above the station and shiftable from a retracted position to an extended position beneath the stack to support the stack thereon when in the extended position, said clamping means disposed above the case supporting means to grip the sides of a case disposed immediately above the case supporting elements, said clamping means responsive to descent of the elevator to clamp that case superjacent the case on the elevator and responsive to an extension of said case supporting elements beneath the clamped case to release the clamping of the case, and said case supporting means responsive to the presence of the elevator in a stack supporting position beneath a stack supported thereby to shift from the extended to the retracted position.

3. A machine for stacking or unstacking cases or the like comprising, in combination: a case conveyor; a case elevator for raising cases from or lowering cases to the conveyor; case-retaining mechanism for holding a case spaced above the conveyor and including first case-supporting means shiftable to and from case-supporting positions beneath a case spaced above the conveyor, and second case-supporting means operable to grip or release the sides of a case spaced above the conveyor; a selective control system for stacking or unstacking operation of the machine and operatively connected to the elevator and retaining mechanism and responsive, when case stacking is selected, to case-elevating movement of said elevator with a case thereon to cause release of a case held by the retaining mechanism as the case on the elevator approaches the held case, to allow stacking of the cases; and said control system responsive, when unstacking is selected,

ed, to the presence of the elevator at a stack-lowering position, to cause said first case-supporting means of the case-retaining mechanism to release the lowest case of the stack and cause the second case-supporting means to grip the sides of the superjacent case as the lower case descends on the elevator toward the conveyor, and responsive to a determined descend of the elevator separating the case thereon from the case gripped by the retaining mechanism to cause said first supporting means to shift beneath the gripped case to support it.

4. The invention as defined in claim 3 characterized in that when case stacking is selected, said control system is operative to cause release of a case held by said retaining mechanism independently of contact of the case on the elevator with such retaining mechanism as the case on the elevator approaches the case held by said retaining mechanism.
